J. G. ROBINSON,
PLUG FOR DRY WELLS,
APPLICATION FILED JULY 12, 1917.

1,263,933.

Patented Apr. 23, 1918.

UNITED STATES PATENT OFFICE.

JOHN G. ROBINSON, OF TULSA, OKLAHOMA.

PLUG FOR DRY WELLS.

1,263,933.

Specification of Letters Patent. Patented Apr. 23, 1918.

Application filed July 12, 1917. Serial No. 180,082.

To all whom it may concern:

Be it known that I, JOHN G. ROBINSON, a citizen of the United States, and a resident of Tulsa, in the county of Tulsa and State 5 of Oklahoma, have invented certain new and useful Improvements in Plugs for Dry Wells, of which the following is a specification.

My invention is an improvement in plugs 10 for dry wells, as for instance, oil or gas wells, to prevent salt water flowing from the said wells that might penetrate gas and oil sands, drowning production in adjacent wells, wherein the plug is so constructed 15 that it may be shipped knocked down and assembled at the well.

In the drawings:

Figure 1 is a sectional view of a well casing showing the plug as it is being lowered, 20 Fig. 2 is a similar view showing the plug lowered and tightened,

Figs. 3 and 4 are enlarged sections on the lines 3—3 and 4—4 respectively of Fig. 1, each view looking in the direction of the 25 arrows adjacent to the line,

Fig. 5 is a perspective view of the body of the plug with one of the wedge blocks detached.

The present embodiment of the invention 30 is shown in connection with a well casing 1, and the improved plug comprises a frusto-pyramidal body portion 2 having upon each face an under cut groove 3, the said grooves being at the centers of the faces.

35 The body of the plug is completed by wedge shaped blocks 4 and 5, each of which is provided on its inner face with an under cut longitudinally extending groove 6, adapted to register with the adjacent groove 40 3 of the body. The outer faces of the blocks are rounded as shown in Figs. 3 and 4, and the blocks 4 and 5 are so shaped that when they are in place on the body of the plug, they will form with the block 2 a cylindrical 45 body. The blocks 4 and 5 are locked to the block 2 by means of keys 7, each of the said keys being shaped to fit the registering grooves 3 and 6 and to fill the same, and to thus lock the blocks 4 and 5 to the block 1.

50 The blocks 4 and 5 are arranged with their large ends upward, while the block 2 is arranged with its large end downward, and a shoe 8 of cast iron or like suitable material is secured to the bottom of the block 1 by a screw 9. The shoe 8 has a reduced portion 55 10 at its upper face of approximately the

same size as the bottom of the block 1, and in its under face is a central threaded opening 11. This opening 11 is engaged by the threaded upper end of a section 12 of pipe 60 which has at its lower end a shoe 13 for engaging the bottom of the well in the manner shown in Fig. 2.

A substantially rectangular frame 14 of lead is connected with the upper ends of the blocks 4 and 5, and the opening through the frame is of sufficient size to receive the small end of the block 1 for some little distance below the said small end. An eye 15 is connected with the small end of the block 1, 70 and this eye is adapted for attachment with a hoisting cable 16 for lowering the plug.

In operation, the plug is assembled on the derrick floor by placing first the sides 4 and 5. The locking keys 7 are placed in the 75 grooves of the block 1, after which the blocks 4 and 5 are placed. The shoe 8 is connected with the bottom of the block 1 and the frame 14 with the tops of the blocks 4 and 5. The hoisting cable is connected with the eye 15 80 and the plug is ready to be lowered into the well after the pipe 12 has been placed. The length of this pipe 12 depends upon the point in the well at which it is desired to place the plug. If for instance, the plug 85 is to be ten feet above the bottom, a ten foot section of pipe is used.

After the plug has been lowered into the well until the shoe 13 strikes the bottom, the blocks 4 and 5 may be forced downward 90 with respect to the block 1, as shown in Fig. 3, until the plug is tightly wedged in the casing. The body of the plug is of soft wood, as for instance cypress, while the keys 7 are of hard wood. No nails or other metals 95 are used in the connection of the plug.

The frame 14 is connected to the blocks 4 by means of straps indicated at 17, the said straps being countersunk in the blocks.

I claim:

1. A device of the character specified, comprising a plug composed of a central frusto-pyramidal block and wedge-shaped blocks fitting the outer face of the pyramidal block, and forming therewith a cylindrical 105 body, said first and last named blocks having on their adjacent faces, registering under cut grooves, keys engaging the registering grooves to lock the blocks together, a spacing member connected with the central 110 block at the bottom thereof, and means connected with the upper ends of the wedge-

shaped blocks for permitting them to be moved downward in unison, for the purpose specified.

2. A device of the character specified, 5 comprising a body composed of a central frusto-pyramidal block and wedge shaped blocks fitting the outer face of the pyramidal block and forming with the said block a cylindrical body, said first and last named 10 blocks having on their adjacent faces registering under cut grooves, and keys engag-

ing the registering grooves to lock the blocks together, a metallic shoe on the bottom of the central block and having a central threaded opening, a pipe threaded into the 15 opening and having a shoe at its other end for engaging the bottom of the well, a lead frame connected with the upper ends of the outer blocks, and a hook connected with the upper end of the central block and extend- 20 ing through the frame.

JOHN G. ROBINSON.
